UNITED STATES PATENT OFFICE.

HENRY H. WAIT, OF CHICAGO, ILLINOIS.

STEAM-TURBINE.

1,315,263.

Specification of Letters Patent. Patented Sept. 9, 1919.

Application filed August 26, 1916. Serial No. 117,086.

To all whom it may concern:

Be it known that I, HENRY H. WAIT, a citizen of the United States, residing at Chicago, in the county of Cook and State of Illinois, have invented certain new and useful Improvements in Steam-Turbines, of which the following is a specification.

My invention relates more especially to the single wheel type of turbine in which the steam is fed to the buckets or blades of the wheel from the side and received from the buckets at the other side of the wheel by reversing guides by which the steam is again directed to the buckets of the wheel whence it goes to exhaust. The invention is more particularly concerned with said return guides and the nozzles by which steam is admitted to the turbine and the arrangement of these parts relative to the casing and other parts of the turbine. A prime object of the invention is to provide a guide which shall be easy and inexpensive to manufacture and to apply to the turbine without sacrificing any of the advantages which are found in connection with more expensive constructions. Other objects and advantages of the invention will appear from the accompanying drawings and the following description in which I have set forth a preferred form of the invention. It is to be understood, however, that the specific disclosure is for the purpose of exemplification only, and that the scope of the invention is defined in the following claims, in which I have endeavored to distinguish it from the prior art without, however, relinquishing or abandoning any portion or feature thereof.

In the accompanying drawings Figure 1 is a side elevation of a preferred form of my invention, the steam inlet, however, being shown in section; Fig. 2 is a fragmentary section on the line 2-2, of Fig. 3 parallel to the plane of Fig. 1; Fig. 3 is a vertical axial section on the line 3-3 of Fig. 1, parts being shown in elevation; Fig. 4 is a development in section on the line 4-4 of Fig. 1; Figs. 5, 6 and 7 are perspective, end and edge views, respectively, of one of the steam return guides removed from the casing; Figs. 8 and 9 are elevations of details of the guides; and Fig. 10 is an enlarged transverse section through a portion of a nozzle, wheel and guide. Each part is

identified by the same reference character wherever it appears in the several views.

The casing of the turbine is or may be composed of a main casting 9 in which the wheel chamber is formed, and which comprises a bracket 10 for supporting the bearing-casting 11, in which one end of the wheel shaft is journaled. The casting 12 forms a face plate fitting upon and bolted to the main casting and closing the wheel chamber. It also comprises a bracket 13 to which the bearing-casting 14 for the other end of the turbine wheel shaft 15 is secured. The face plate is formed with openings 16, 16^a, surrounded by external bosses 17 which receive the nipples 18 which carry the nozzles 19^a, 19^b, (see Fig. 4). Nipples 18 are formed with external flanges 20 which are perforated and secured between the unions 21 and 22, and the bosses 17, by bolts 23 extending through the flanges on said unions, the flanges on the nipples and into the face plate. In the construction selected for exemplification a main and an auxiliary nozzle are employed, the main nozzle being indicated by the character 19^a, and the auxiliary nozzle by the character 19^b, but it will be obvious that the auxiliary nozzle is not essential, but may be used to increase the power of the turbine. Where the main and auxiliary nozzles are employed, however, they are connected together as by a pipe 24, connected by flanges 25, 26, to similar flanges upon the unions.

The nozzles are screwed into the ends of the nipples, projecting at the acute angle to the side or face of the turbine wheel, and are slightly flared and cut away upon one side on a plane parallel to the face of the turbine wheel so that they fit closely to the edges of the series of buckets, but have a slight clearance therefrom. For the purpose of the present invention the precise construction of the wheel and buckets is not material provided the latter are of the well known curved type. The wheel shown for the purpose of illustration is a disk 27 of metal plate, perforated at 28 to receive the axle and provided upon opposite sides thereof with perforated disks 29 riveted thereto and forming hubs therefor to brace the wheel with relation to the axle. The plate disk is cut away upon one side at 30 to form an annular groove of the cross-section

shown in Fig. 3 concentric with the disk and adjacent its periphery. The lateral flange 31 so formed is slightly chamfered at 32, and its periphery forms a seat for the buckets 33, which are secured thereto by rivets or bolts 34. By chamfering the flange of the wheel, the corresponding face of the latter is brought flush with the buckets notwithstanding that the latter are short and at the same time symmetrical with respect to the rivets by which they are secured to the wheel. A band 35, which may be integral or in sections, but preferably the former, surrounds the buckets and is also held by the rivets which are upset or headed over outside the band. The main casting 9 and the face plate 12 are each formed with stuffing boxes 36, 37, within which sectional packing rings 38, 39 are maintained in engagement with the shaft by means of spiral spring rings or garters 40; cover plates 41, 41 are bolted to the main casting and face plate respectively for closing the stuffing boxes. The main casting and face plate are each formed with a series of radial strengthening ribs 42, 43, and the main casting 9 is formed with a pocket or pockets 44 projecting outwardly between said ribs and which receive the steam return guides to be presently described.

The guides consist each of a supporting member 45, a cover plate 46, and an intermediate series of guide ribs or blocks 47. (See Figs. 5 to 8 inclusive.) The support 45 comprises a rib 48 and a curved plate 49, the rib being formed with bolt holes 50, 51, by which the support is bolted to bosses 52 formed upon the casing. (See Fig. 3). The curved plate 49, when the support is bolted in place, is concentric with the wheel. The guide blocks or ribs, the outlines of which are best shown in Figs. 4 and 8, are cast in brass and preferably in a single casting connected by bridges or webs 53. (See Fig. 8). These blocks comprise an outer marginal wall 54, an inner block 55 tapered throughout except at the larger end where it is rounded as at 56, and one or more crescent shaped blocks 57, 58 which are so shaped and arranged as to provide two or more curved channels 59, 60, 61, to receive the steam from the buckets of the wheel after it has been delivered thereto by the nozzle, and after substantially reversing its direction deliver it to a common channel 62 by which it is again returned to the buckets of the wheel. Preferably the steam return guide is assembled into a unit before being applied to the turbine, and after the intermediate member in which the channels are formed has been applied to the support, so that its various elements are fixed relative thereto, the bridges or webs, to which reference has been made, are cut away leaving smooth channels for the steam and the

edges of the blocks 63, 64 are filed to sharp chisel edges.

The combined cross-sectional area of the channel or channels of the guide passages is approximately uniform throughout as will be understood by those familiar with this art. This cross-sectional area is dependent to a certain extent upon the peripheral speed of the wheel, so that with a given circumferential span of the nozzle on the wheel blades 75 it is desirable to be able to vary this cross-sectional area without restricting the circumferential span of the entrance to the guide passage so that the steam emerging from the wheel blades would impinge on 80 dead walls as at 54, 55 in Fig. 4. To this end it is sometimes advisable to make the radial depth of the main part of the guide passage, as at 70 in Fig. 10, less than the radial height of the wheel blades, and the 85 entrance to this passage can then be flared as shown in Fig. 10, so that the steam jet emerging from the wheel will not impinge against the inner and outer circumferences of the passage. With a view to avoiding 90 the impinging of the steam jet on the edges of the wheel and wheel band at the discharge end of the guide passages, I slightly file away, or chamfer the intermediate members as at 65, (see Figs. 4 and 8) so as to 95 make the face thereof adjacent the wheel of slightly less width at this portion, and when the cover is applied thereto it is bent or swaged down at 65^a (Figs. 7 and 9) to fit snugly against the chamfered edge, by 100 which means the channel at its outlet is slightly reduced in diameter as compared with the original diameter and with the radial dimension of the buckets. At the receiving end the channels are widened by 105 filing, cutting away, or chamfering the cover plate and support at 66, 67, (see Figs. 9 and 10) in register with the channels of the intermediate member, so that the inlet ends of these channels are slightly flared 110 and thus widened beyond the radial dimension of the buckets. After the several elements of the guide have been treated in the manner just described, they are assembled and riveted together by the rivets 69, when 115 the guide is ready for application to the turbine casing. Thus the entire making and assembling of the guide is accomplished outside the turbine casing and the riveting of the parts together may be accomplished at 120 a single operation. The return guide is then bolted to the ribs of the casing as heretofore described.

It is sometimes desirable to be able to mount the turbine for right or left-hand rotation. For this purpose no change in the casing is required, but the wheel or the buckets thereon must be reversed and the nozzles turned through an angle of 180 degrees to the position shown in dotted lines 130

in Fig. 4. The steam guides must also be reversed in direction as shown in dotted lines in said figure. In order to avoid duplication of bolt holes for securing the guides 5 in the opposite positions when the casing is constructed to permit of reversal of rotation, I form one of the bolt holes in the casing directly opposite the aperture for the nozzle with which the guide to be secured by said 10 bolt hole cooperates, and the rib 48 is extended at the receiving end of the guide beyond the latter, and the hole 50 formed therein through which that end of the guide may be secured to the casing by a bolt passing 15 through said holes in the guide and casing respectively. (See Fig. 5).

I claim:

1. A return guide for a steam turbine of the axial flow reentrant type, comprising a 20 cylindrically curved supporting member, cylindrically curved channel strips arranged upon the cylindrical surface of said member and so spaced from each other as to form axially reentrant steam passages and a separate 25 cover plate fitting over said strips.

2. A steam return guide for a steam turbine of the axial flow reentrant type comprising a cylindrically curved supporting member having an external longitudinal 30 stiffening and supporting rib thereon, and adapted for attachment to the side wall of a turbine, channel strips secured upon the cylindrically curved face of the supporting member and so spaced as to form suitable 35 steam channels, and a cover plate fitting over said strips.

3. A steam return guide for a steam turbine of the axial flow reentrant type comprising a support consisting of a tapering 40 cylindrically curved plate, and a rib normal thereto and adapted to be secured to the side wall of the casing of a turbine, a plurality of cylindrically and axially curved channel strips secured to the cylindrical face 45 of the support, and so spaced as to form therewith suitable steam passages, and a cover plate arranged over said strips.

4. A steam return guide for a steam turbine of the axial flow reentrant type comprising a support consisting of a cylindrically curved plate, tapering toward one end, a rib arranged longitudinally of said support and adapted to be secured to a casing of a 50 turbine, channel strips upon the cylindrical face of the support, and a cover plate arranged over said channel strips.

5. In a steam turbine of the axial flow reentrant type, a casing comprising opposite relatively parallel walls and a web connecting 55 said walls, a shaft extending through said walls, a turbine wheel mounted on said shaft, a nozzle mounted on one of said walls and adapted to supply the turbine wheel with steam, a pocket formed in the other of

said walls, and a steam return guide co-operating with said wheel extending into said pocket and a flange on said guide by which the same is secured to the face of the wall in which said pocket is formed. 65

6. In a steam turbine, a casing comprising 70 a pair of substantially parallel walls, a web connecting said walls, a nozzle secured in one of said walls, a shaft extending through said walls, the turbine wheel mounted on the shaft, the other of said walls being formed with a recess, a separate steam return guide structure extending into 75 said recess, and comprising a support having a rib thereon, and axial bolts securing said rib to the face of the last said wall. 80

7. In a turbine of the class described, a steam return guide of the axial flow type comprising a support, a separate cover plate and a series of channel strips between said support and cover plate so spaced as to form 85 between them channels for receiving the steam from the turbine wheel and returning it thereto.

8. A return steam guide for a steam turbine of the axial flow reentrant type, comprising a cylindrical support, a cover plate and channel strips curved circumferentially and axially arranged between said support and plate, said channel strips being of substantially constant height in the main part 90 of the passage but chamfered near the outlet end of the channels therein, and said cover plate being bent to fit against the chamfered portion of said strips. 95

9. A steam return guide having a steam 100 turbine of the axial flow reentrant type comprising a support having a cylindrical surface, strips supported on said cylindrical surface and spaced apart from each other to form return channels for the steam, said 105 channels being curved circumferentially and axially, and a cover plate secured to said strips and support, and having its edges adjacent the passages between said strips 110 chamfered to produce a flare in the mouths of the channels.

10. In a steam turbine, a steam return guide comprising a support, consisting of a cylindrical guide portion and a radial rib portion extending at one end beyond the 115 body of the guide and formed for attachment to the casing of the turbine.

11. A guide for a steam turbine of the axial flow type adapted to receive a jet of steam discharged from the blades of the 120 wheel and direct said steam jet to a second impact with the same wheel, said guide being cylindrically curved having a steam passage therein flared at the receiving end, the intermediate portion of the steam passage 125 being of substantially uniform cross section.

12. A guide for a steam turbine of the axial flow type adapted to receive a jet of

steam discharged from the blades of the wheel and direct said steam jet to a second impact with the same wheel, said guide having a steam passage therein flared at the receiving end and constricted at the discharge end, the intermediate portion being of substantially uniform diameter.

13. A steam turbine comprising a wheel with radial blades and a casing, said wheel 10 being chamfered at the rim, a return guide adapted to receive a jet of steam discharged from the blades of the wheel and consisting of a cylindrical supporting member having guide strips secured thereto, said supporting

member being chamfered to correspond with 15 the chamfer of said wheel.

14. A steam turbine comprising a casing and a wheel, the latter having buckets thereon, a return guide having a passage therein of approximately constant cross section 20 adapted to receive steam discharged from the blades of the wheel, the main part of said passage being of less height than the wheel blades and the receiving end of said passage being flared to a greater radial 25 height than said wheel blades.

HENRY H. WAIT.
